(57) **CLAIM**

The ornamental design for an eyewear, as shown and described.

DESCRIPTION

FIG. 1 is a perspective view of the new design for an eyewear, according to a first embodiment;

FIG. 2 is a front view thereof;

FIG. 3 is a rear view thereof;

FIG. 4 is a top view thereof;

FIG. 5 is a bottom view thereof; and,

FIG. 6 is a left side view thereof, the right side view being the mirror image thereof.

The broken lines illustrate portions of the eyewear that form no part of the claimed design.

1 Claim, 6 Drawing Sheets
